Inventor

Wallace Durand,

By Stace & Co Atty's.

UNITED STATES PATENT OFFICE.

WALLACE DURAND, OF NEWARK, NEW JERSEY.

DESIGN FOR A WATCHCASE.

SPECIFICATION forming part of Design No. 23,265, dated May 15, 1894.

Application filed April 19, 1894. Serial No. 508,221. Term of patent 7 years.

To all whom it may concern:

Be it known that I, WALLACE DURAND, a citizen of the United States, residing at Newark, in the county of Essex and State of New Jersey, have invented and produced a new and original Design for Watchcases; and I do hereby declare the following to be a full, clear, and exact description of the invention, such as will enable others skilled in the art to which it applies to make and use the same, reference being had to the accompanying drawings, and to letters of reference marked thereon, which form a part of this specification.

Figure 1 is a face view of the watch case and Fig. 2 is an edge view of the same, these two views being deemed necessary to fully illustrate the design.

The leading feature of the design consists in the watch case which is round in plan, and convexly curved at the edges and at the cen-

ter is approximately flat, the said flat center presenting a bull-shaped decoration.

In said drawings, *a*, indicates the round face of the watch case, which is convexly curved at its edges and, at its center, is more or less flat as indicated in Fig. 2. The flat center part is ornamented by a bull-shaped figure, *b*, and below the same, an ornament resembling the zodiacal signs for Taurus.

What I claim as new is—

The design for a watch case, substantially as shown and described.

In testimony that I claim the foregoing I have hereunto set my hand this 27th day of January, 1894.

WALLACE DURAND.
